(57) **CLAIM**

The ornamental design for a bottle rack, as shown and described.

DESCRIPTION

FIG. 1 is a perspective view of a bottle rack showing a new design;

FIG. 2 is a front view thereof, the rear being a mirror image;
FIG. 3 is a left side view thereof, the right side view being a mirror image;

FIG. 4 is another perspective view of the bottle rack of FIG. 1 in use;

FIG. 5 is a front view thereof, the rear being a mirror image;
FIG. 6 is a left side view thereof, the right side view being a mirror image;

FIG. 7 is a perspective view of the bottle rack of FIG. 1 showing a second embodiment;

FIG. 8 is a front view thereof, the rear being a mirror image;
FIG. 9 is a left side view thereof, the right side view being a mirror image;

FIG. 10 is another perspective view of the bottle rack of FIG. 7 in use;

FIG. 11 is a front view thereof, the rear being a mirror image;
FIG. 12 is a left side view thereof, the right side view being a mirror image;

FIG. 13 is a perspective view of the bottle rack of FIG. 1 showing a third embodiment;

FIG. 14 is a front view thereof, the rear being a mirror image;

FIG. 15 is a left side view thereof, the right side view being a mirror image;

FIG. 16 is another perspective view of the bottle rack of FIG. 13 in use;

FIG. 17 is a front view thereof, the rear being a mirror image;

FIG. 18 is a left side view thereof, the right side view being a mirror image;

FIG. 19 is a fourth embodiment of the bottle rack showing a cut-away view; and,

FIG. 20 is a cross-sectional view of the bottle rack taken along line 20-20 in FIG. 2.

In the Figures the dash-dash broken lines are for the purpose of illustrating environment and form no part of the claimed design.
